UNITED STATES PATENT OFFICE.

JOHN RYLE, OF PATERSON, NEW JERSEY.

WARPING-MACHINE.

SPECIFICATION forming part of Letters Patent No. 317,472, dated May 5, 1885.

Application filed January 29, 1884. (No model.)

To all whom it may concern:

Be it known that I, JOHN RYLE, a citizen of the United States, residing at Paterson, Passaic county, State of New Jersey, have 5 invented a new and useful Improvement in Warping-Machines, of which the following is a specification, reference being had to the accompanying drawings, forming a part thereof.

The invention consists of the devices and 10 combination of devices illustrated in the drawings, which will be hereinafter fully explained.

Figure 1 of the drawings is a side elevation of a machine embodying my invention. Fig. 2 is a plan view thereof. Fig. 3 is a front view 15 of some of the parts shown in Fig. 1. Fig. 4 is also a front view of some of the parts shown in Fig. 1. Fig. 5 shows the front of the machine in elevation. Fig. 6 shows a part of the driving mechanism in elevation. Fig. 7 is a 20 plan of measuring mechanism. Fig. 8 is a part plan of traverse mechanism; and Fig. 9 is an enlarged view of some of the parts shown in Figs. 1 and 5.

A represents a power warping-machine having 25 a frame, A', on and to which frame are arranged and secured various devices and driving mechanism, as follows: Suitably located on the upper part of the machine and secured to the frame A' there is a stud, b², on 30 which stud there are journaled pulleys b, one of which—the outer one—is loose, and the inner one—the main driving-pulley—is provided with a sleeve which carries a pinion, c, that meshes with a gear-wheel, c'. This wheel 35 is arranged on and secured to one end of a shaft, c². This shaft is journaled in bearings in the frame A', and has at its other end a worm, e⁴, fast on said shaft, which meshes with a worm-wheel, f', fast on a transverse shaft, 40 f, which is journaled in bracket-bearings g g, secured to the frame A'.

More centrally located on and secured to the shaft f there is a cam, f², which cam engages 45 with a roller, f³. Said roller is journaled on a stud that is suitably secured to a lever, f⁴, which lever is pivoted at its lower end to a bracket on a pivot, f⁵; the lever f⁴ connects by a link, h, to a lever, h'. Said lever is suitably arranged in a bracket that is suitably secured to a transverse bar, d, which bar is horizontally arranged in brackets d' d'', that are secured to the frame A'.

The bracket d⁴ is provided with glass guides d⁵. The cord h², provided with a weight, h⁵, passes over a grooved pulley, h⁴, and is secured to the lever h'. The pulley h⁴ is journaled in a depending arm that is secured to the top or table a.

On laterally-projecting arms k¹¹, secured to the frame of the machine, there are journaled 60 in bracket E, secured to said projecting arms k¹¹, rollers k' k², and in the arms k¹¹ a measuring-wheel, k, having a shaft, k¹⁰, on which shaft there is arranged and secured a worm, k³, that meshes with a gear-wheel, k⁴, having 65 a pinion, k⁵, that meshes with a gear-wheel, k⁶, which wheel is provided with a stud, k⁹, that engages with a hammer, k⁸. This hammer is secured to the frame A', and is so arranged as to strike the gong k⁷. The wheel 70 k⁴ and its pinion k⁵ are arranged on a stud, k¹², and the wheel k⁶ and gong k⁷ are arranged and journaled on a stud, k¹³, as shown in Fig. 9. Suitably secured to the frame A' are arms 75 k¹ k², in which arms is journaled a horizontal spindle, l⁷, provided with a bobbin, l, gear-wheel l⁵, and screw l¹, as shown in Fig. 6. Located at some distance from the machine proper there is a movable frame, B, having arranged and secured thereon a reed, n', and 80 glass rod n³. Said rod is arranged in brackets n⁶ secured to flap n⁴. The frame is provided with a flap, n⁴. Said flap is provided with hinges n⁵. The frame B is supported on standards r' r², Fig. 4. More remote from the 85 machine A' there is arranged a creel-frame, p, which frame is supported by standards s, and is provided with a reed, n, having dents r and pins p², and supply-spools p', as shown in Figs. 1, 2, and 3. The machine is provided 90 with the ordinary belt-guide b'.

The operation of the machine is as follows: Motion is given to the pulleys b by the ordinary means employed therefor, which motion, by means of pinion c and gear-wheel c', rotates the shaft c², and by means of gear-wheels l⁶ l⁵, worm l⁴, and worm-wheel f', rotates the spindle l⁷, its bobbin l, and shaft f, which shaft in turn, by means of cam f² and roller f³, reciprocates the lever f⁴. This lever, by means 95 of link h, cord h², pulley h⁴, and weight h⁵, imparts a reciprocating motion to the lever h'. Pivoted to the frame at h³, which lever, in its 100 connection with traverse-bar d, gives a hori-

zontal reciprocating motion to said bar. The parts mentioned having been put in motion in the manner stated, the several strands are taken from the spools p' upward through the 5 reed n and between the dents r , and through the reed n' forward to and through the reed n^2 , which last-mentioned reed is arranged as illustrated in the drawings. After the strands D have been taken through the reeds 10 n n' n^2 in the usual and well-known way, the warp end is passed over the top of the roller k^2 , down under and around the wheel k , upward and over the roller k' , forward to the bobbin l and between the guides 15 d^3 , and is secured to the bobbin l in the usual way. The bobbin l , which is secured to the spindle l' by means of screw e' , being in rotation, draws the strands D which compose the warp from the spools p' through 20 the reeds over rollers and measuring-wheel in the manner stated, and the warp thus formed and drawn by the bobbin l is laid evenly on and distributed over the same by the bar d , which bar is reciprocated by the 25 traverse mechanism. The measuring-wheel k , having been put in rotation by the draft on the warp-strands D, caused by the rotation of the bobbin l by means of the worm k^3 , rotates the worm-wheel k^4 , the pinion k^5 rotates the wheel k^6 , which by means of stud k^9 30 actuates the hammer k^8 . Said hammer in its action strikes the gong k^7 , and thus indicates the number of yards measured and wound on the bobbin l , by which means the warps are 35 and can be made of even length, as follows: The wheel k having a measuring capacity of one yard at each revolution of the same, and the wheel k^6 having been arranged by intermediates k^4 k^5 to have one revolution to 40 every sixty revolutions of the wheel k , it then follows that every action of the hammer k^8 on the gong k^7 will indicate sixty yards measured by the wheel k and laid on the bobbin l , and if the length of the warp is fixed 45 at one hundred and eighty yards the wheel

k would make as many revolutions, and the wheel k^6 would have made but three revolutions, and would have so indicated by its action on the gong k^7 by means of the stud k^9 and hammer k^8 .

50

It will be understood that by changing the intermediates a greater or less number of yards may be indicated at every revolution of the wheel k^6 . The tension on the warp-strands D is regulated as follows: The reed 55 n being more elevated than the reed n^2 , as illustrated in Fig. 1, causes the tension or strain on the strands D to be increased as the frame B is moved nearer to the reed n^2 , and, vice versa, when the frame B is placed nearer 60 to the reed n , the tension or strain on the strands D is made less.

55

When it is desired to remove the tension and slacken the warp-strands, the hinged flap n^4 , that carries the rod n^3 , may be let down, 65 which action will allow the warp-strands to fall and thus remove all strain from the same.

65

Having described my improved warping-machine and its operations, I claim and desire to secure by Letters Patent—

70

1. The frame B, having a vertically-movable flap and a bar attached thereto, over which the warp-threads pass, in combination with the devices for supplying and winding the yarn, substantially as set forth.

75

2. The hinged flap n^4 , in combination with a frame to which is attached a glass bar attached to said flap, over which the warp-threads pass, and the devices for supplying and winding the yarn, substantially as set forth.

80

3. The hinged flap n^4 , carrying the glass rod n^3 , in combination with the frame B, to which it is attached, and the yarn-supplying and yarn-winding devices, substantially as set forth.

85
